UNITED STATES PATENT OFFICE

HENRY H. SERVICE, OF TOPEKA, KANSAS

COUPLER

Application filed May 20, 1930. Serial No. 454,002.

My invention is more especially intended for use in connection with what is known as an American Railway Association type D coupler and the invention relates more particularly to means whereby the coupler is maintained in locked position.

In the specific embodiment of the invention, it comprises a special type of lock lifter which is adapted to the present standard type of coupler, whereby a wedging relation is effected to maintain the lock lifter in anti-creep position or relation with the coupler head or main body.

The objects and advantages of my invention will be readily comprehended from the detailed description of the accompanying drawing, wherein:—

Figure 1 is a side elevation of a coupler, with parts broken away and shown in section to disclose my improved lock lifter which is shown in side elevation and in coupler locking position.

Figure 2 is a similar view illustrating the coupler in complete unlocked position.

Figure 3 is a detail sectional view taken substantially on the line 3—3 of Figure 2 as viewed by the arrows.

Figure 4 is a perspective view of my improved lock lifter.

My invention relates particularly to the lock lifter as employed in the present standard type of A. R. A. coupler as illustrated in the drawing, wherein the main head or body of the coupler is shown at 10 which is formed to provide the usual chamber in which the respective elements of the coupler are located; the top of the chamber and therefore the top wall of the coupler body having an opening 11; while the rear wall of the chamber has a depending portion or rear wall 12 for the purpose hereinafter set forth.

The coupler knuckle 13 is swingingly held in place by the usual pin 14 shown in dotted lines; and the knuckle is provided with the usual tail 15 which extends into the chamber

formed in the coupler body 10 and which is held in locked position by the lock block or member 16.

The lock member 16 has a depending leg 17 which on its rear edge is provided with a lockset seat 18 which permits the lock member to rest or seat on the knuckle thrower or kicker 19 when the coupler is set for coupling operation. The thrower or kicker 19 is oscillatingly mounted in the coupler head in the usual manner so that when the lock 16 is lifted into coupler unlocking position, the leg 17 of the lock 16 will engage the adjacent end of the thrower, causing the latter to oscillate, thereby forcing its opposite end against the tail of the knuckle and moving the latter into uncoupling position, as shown in Figure 2.

The lock block or member 16 in its upper end is vertically slotted as shown at 20, which slopes and curves upwardly at the front end of the slot, see Figure 3; the slot 20 being extended and also opening at the rear side of the lock member 16.

This slot at its lower end is laterally enlarged to provide recesses as shown at 21 in Figure 3 to receive the laterally extending trunnions 22, 22, formed on the lower end of the lock lifter 23, shown in perspective in Figure 4.

The trunnions 22, 22 are adapted to slide in the upwardly sloping enlarged lower end or recesses 21 of the slot 20 in the lock member 16 during operation of the coupler. That is to say, the trunnions 22, 22 normally are located adjacent to the rear end of the recesses in the lock member 16, thus, during unlocking operation, exerting an upward pull on the lock member at a point rearward of its center of gravity so that there is a constant tendency for the depending leg 17 of the lock member 16 to swing rearwardly as soon as the lock member is lifted.

Further upward movement of the lock member 16 causes its fulcrum point or for-

ward extension 24 to strike the shoulder 25 within the coupler head 10. Engagement of the extension 24 with the shoulder 25 causes the lock member 16 to rotate about its fulcrum 24 thereby positively moving the lock leg 17 rearwardly so as to oscillate the knuckle thrower or kicker 19.

The lock lifter 23, adjacent to its lower end and on what may be termed the rear edge, is provided with the somewhat stepped extension or projection 26. This projection 26 is adapted to underlie the lower edge of the rear wall portion 12 when the coupler is in locked position, as shown in Figure 1. This projection and arrangement is intended to prevent the lifter and lock member from creeping or moving upwardly during train operation. Positive upward movement or pulling on the lifter 23 causes the trunnions of the lifter to slide forward and upward in the sloping recesses of the slot in the lock member and free the engagement of the projection 26 with the depending rear wall 12.

It has been found in practice, however, in the type of coupler herein defined, that the so-called anti-creep features,—viz. projection 26 and rear wall lug or extension 12—fail to function at all times and thus allow the lifter and lock member to move into unlocking position and hence permit the coupler to move to uncoupling position; this undesirable movement being due to the fact that the trunnions 22 of the lifter 23 creep forwardly in recesses 21 of the slot 20 in the lock member 16, causing the extension or projection 26 to move away from the rear wall extension 12.

This permits the lock member 16 with the lifter 23, due to constant vibration during train operation, to gradually move upwardly out of knuckle holding or locking position.

My invention is especially designed to prevent this undesirable, accidental movement of the coupler elements.

I therefore provide the lifter 23, on its forward side and adjacent the lower slightly rearwardly curved end thereof, with a forwardly disposed projection or lug 27, seen more clearly in Figure 4.

The projection or lug 27 is so formed and made of such size that it will contact with the forward upwardly sloping bottom wall of the slot 20 in the lock block 16 when the extension or anti-creep projection 26 is in engaging relation with the rear wall projection 12 while the lock block 16 is in the coupler locking position shown in Figure 1; the lug 27 being arranged substantially in the same horizontal plane as the notch in lug 26 and with the forward end of the curved face of lug 27 riding in the bottom of the slot it exerts a pressure in a horizontal direction toward the rear and hence holds the notch or recess of lug 26 in engagement with the wall projection 12.

With the projection or lug 27, improper or

accidental upward movement of the lock block 16 and movement of the lifter 23 out of anti-creep position will be prevented because the projection or lug 27 is in contact with and bears against the forward upwardly sloping surface of the slot in the lock block 16 which tends to force the lower end rearwardly and maintain the lower end of the lifter 23 with its anti-creep extension 26 in position against the depending rear wall portion or anti-creep lug 12 of the coupler head 10 and thus prevents the possibility of the lock block 16 accidentally shifting to unlocking position when the coupler body or head 10 strikes the buffering block on an adjacent car or locomotive.

With the lug 27 located adjacent to the lower and somewhat rearwardly curved end of the lifter element 23 and substantially in the same horizontal plane as the notch or depression in the stepped projection 27, it is apparent that a direct upward pull on the lifter will cause the lug 27 to be moved upwardly out of contact with the lower wall of the slot 20 in the lock block 16 allowing the lower end of the lifter to move forwardly in the slot and thus permit the anti-creep projection 26 of the lifter to move out of interengaging relation with the depending rear wall portion 12 of the coupler head.

As is apparent, my improved lifter element is applicable for use with the present standard elements of a coupler of the type herein defined, namely with a lock block, knuckle and thrower or kicker which latter elements are permitted to function in their usual manner without interference.

I have shown a specific exemplification of my invention as applied to a standard type of A. R. A. coupler adapted for what is known as top operation of the lifter element and have described the same in terms employed merely as terms of description and not as terms of limitation, as structural modifications are possible and may be made without, however, departing from the spirit of my invention.

What I claim is:

A coupler of the class described comprising a chambered coupler head having an opening in its top and a depending rear wall portion in the chamber; a vertically movable lock member in said chamber provided in its upper end with a slot having a bottom wall sloping upwardly toward the front side of the member, the lower rear end of the slot having elongated recesses on opposite sides; a lifter member having laterally disposed trunnions seated in said recesses of the lock member, the rear side of the lifter member having a recessed projection adapted to engage with the rear wall projection in the chamber while the forward side of the lifter member above the plane of the trunnions has a forward projecting lug having a curved surface at its tip, said lug being disposed substantially in the same horizontal plane as the notch in the rear wall projection.

plane as the recess in the rear projection of the lifter, the curved tip of said lug contacting with the upwardly sloping bottom wall of the slot in the lock member and thereby exerting rearward force on the lower end of the lifter and maintaining the rear recessed projection in contact with the depending wall portion of the head, whereby accidental upward movement of the lock member is prevented.
